END STANDARD FOR A CHURCH PEW OR THE LIKE

William H. Kessler, Grosse Pointe Park, Mich., assignor
to Meathe, Kessler & Associates, Inc., Grosse Pointe,
Mich., a corporation of Michigan

Filed Nov. 16, 1961, Ser. No. 67,555

Term of patent 7 years

(Cl. D15—8)

FIG. 1

FIG. 2

FIG. 3

FIG. 4

FIG. 5

FIG. 6

FIG. 7

FIGURE 1 is a top plan view of an end standard for a church pew or the like showing my new design;

FIGURE 2 is a front elevational view of the end standard shown in FIGURE 1;

FIGURE 3 is a side elevational view of the end standard;

FIGURE 4 is a rear elevational view;

FIGURE 5 is a sectional view taken on the line 5—5 of FIGURE 3;

FIGURE 6 is a sectional view taken on the line 6—6 of FIGURE 3; and

FIGURE 7 is a sectional view taken on either line 7—7 or FIGURE 3.

The dotted lines in FIGURE 3 are for illustrative purposes only.

I claim:

The ornamental design for an end standard for a church pew or the like, substantially as shown and described.
